UNITED STATES PATENT OFFICE.

ROBERT C. SMITH, OF OAK PARK, ILLINOIS.

DESIGN FOR A DIAL-CASE FOR LIQUID-GAGES.

45,160.

Specification for Design.

Patented Jan. 13, 1914.

Application filed October 21, 1912. Serial No. 727,085. Term of patent 14 years.

To all whom it may concern:

Be it known that I, ROBERT C. SMITH, a citizen of the United States, residing at Oak Park, in the county of Cook and State of Illinois, have invented a new, original, and ornamental Design for Dial-Cases for Liquid-Gages, of which the following is a specification, reference being had to the accompanying drawing, forming a part thereof.

Figures 1 and 2 are respectively side and

front views of a dial case for liquid gages, showing my new design.

I claim:

The ornamental design for a dial case for liquid gages, as shown.

ROBERT C. SMITH.
